CLAMP

Romeo A. Lalli, Bridgeport, Conn.

(1805 Stratford Ave., Stratford, Conn.)

Original application Apr. 2, 1956, Ser. No. 575,470, now Patent No. 2,889,865, dated June 9, 1959. Divided and this application Oct. 21, 1958, Ser. No. 768,703

2 Claims. (Cl. 24—263)

This invention relates to a manually operated clamp means. More specifically, it pertains to a clamp adapted to grip the edge of a sheet of metal or like material for exerting a pulling force thereon.

The application is a division of my copending application Serial No. 575,470, filed April 2, 1956, now Patent No. 2,889,865.

It is an object of the present invention to provide a clamp adapted to exert a strong gripping force and one which is readily movable into and out of clamping relation.

Another object of the invention is to provide a clamp which is particularly useful in the gripping of the end of a metal sheet to provide a pulling action thereon without damaging the sheet.

A further object of the invention is to provide a clamp which is universally mounted to that it can accommodate itself to the direction of pull on the material gripped thereby.

A still further object of the invention is to provide a clamp having a fixed jaw member and a movable jaw member, with manually operated cam means operably engaging the movable jaw member for shifting it relative to the fixed jaw member.

A feature of this invention resides in means whereby the opening and closing of the jaw members of each unit is accelerated by simple rotary action exerted on the actuating means of the clamping jaw.

Other features and advantages will be apparent from the specification and claims when considered in connection with the drawings in which:

FIGURE 1 is a side view of an individual clamping jaw.

FIG. 2 is an enlarged detail side view partly shown in section of the clamping jaw.

FIG. 3 is an enlarged detail front view partly shown in section of the clamping jaw.

The invention is directed to clamps of the type which are adapted to grip metal or sheets of like material and maintain a grip thereon against great amounts of pulling force. Though the clamp may be utilized in a variety of ways and in conjunction with varied types of apparatus, reference hereafter is made, in order to facilitate the disclosure, to its use in an apparatus of the stretch press type.

According to the invention, a base plate 29, of a stretch press or the like can have mounted thereon one or more individually operated clamping jaw units 30. The individual units include an L-shaped base portion 35 having the base leg 35a slidably and pivotally mounted to the base plate 29 for rendering the unit transversely adjustable along a slot 34. A stud 36 projecting upwardly through the slot secures the base portion 35 of the unit to the base plate, the head 36a of the stud being retained in the T-slot. The upwardly extending leg portion 35b of the base portion 35 is provided with a transversely extending bore for receiving a pin 37 about which a jaw member 38 is pivoted so that it may be tilted with respect to the base plate 29 as may be required, the upper portion of the jaw member being provided with a gripping portion 38a. Secured to the jaw member by suitable fasteners 39 is a bracket 40 which is provided with a recessed por-

2

tion 41, the recessed portion being adapted to be positioned opposite the gripping portion 38a of the jaw member. Mounted in the recess 41 of the bracket is a second or normally retracted, movably mounted clamping jaw member 42 which is adapted to be moved relative to the fixed jaw member 38. This is accomplished by supporting the movable jaw member 42 on the bracket 40 by a plurality of pin members 43 which are slidably mounted in transversely extending bores 44, a portion of each bore 44 being enlarged to accommodate a coil spring 45 which normally tends to urge the pin members 43 and attached jaw member 42 into retracted position within the recess, as shown in FIG. 2. If desired, the face of the movable jaw member 42 may be provided with serrations 42a to securely grip the material disposed between the jaw members.

According to this invention, each clamping jaw unit 30 is provided with an individual operating means by which the jaws can be individually operated by a simple manual operation. As shown in the drawings, the means for operating the movable jaws comprises a shaft 49 mounted in a transverse bore in the bracket 40 and having an eccentric camming portion 49b thereon which engages a dowel or roller 47 disposed in a passage 46, while roller 47 engages a recess 42b in the back of the movable jaw. Shaft 49 is rotatably mounted on the bracket 40 in a transversely extending bore, the ends 49a of the shaft being in bearing relationship in the bore of the bracket. The eccentric camming portion 49b engages the roller 47 so that upon rotation of the shaft 49, the eccentricity of the intermediate portion 49b of the shaft displaces the roller 47 laterally, thereby advancing the jaw member 42 into clamping position.

To facilitate rotation of the shaft 49, a manual operator 50 is provided. As illustrated in FIGS. 1 to 3, the operator comprises a rod 51 having a knob 52 fixed to the upper end thereof, the rod 51 being connected to the shaft 49 intermediate the ends thereof. As illustrated in FIG. 2, the bracket 40 is provided with a slot 53 to accommodate for rotation of the handle for clamping and unclamping the jaw members.

In order that the movable jaw member 42 may be accelerated to its clamping and unclamping position upon actuation of the actuating means 50, the eccentric cam portion 49b of the shaft is provided with a longitudinally extending recess 49c which is adapted to receive the roller 47. Therefore, with reference to FIG. 2, it will be noted that in normal, open jaw position the roller 47 is in the recess 42b of the jaw member and recess 49c of the cam. Thus, as the handle 50 is rotated, counterclockwise as viewed in FIG. 2, the shaft is rotated counterclockwise causing the camming surfaces 49d of the eccentric camming portion 49b to engage the roller 47 to quickly cam or displace the roller 47 laterally and to the right to move the clamping jaw 42 into clamping position onto the marginal portion of a thin sheet material (not shown) disposed between the jaw members. Because of the roller being normally seated in the recess 49c, it will be noted that maximum lateral displacement occurs during the initial rotation of the handle whereby the roller 47 is forced out of the recess 49c to move the movable jaw member into clamping position. Continued rotation of the shaft 49 causes the outer camming surface 49d of the shaft to wedge the roller against the movable jaw member to lock the same in clamped position. Conversely, it will be noted that in unclamping the sheet, the shaft 49 is rotated clockwise from clamped position to the position illustrated in FIG. 2. As a result, the gripping action is gradually released until the instant the recess 49c is aligned with the roller 47, whereupon the latter is quickly snapped into seated position due to

the action of the springs 45 normally biasing the jaw member 42 to open position. Consequently, it will be noted that the accelerated feature of the novel clamping jaw herein described greatly reduces the amount of time involved in opening and closing of the clamping jaw units 30. Further, the clamping means of this invention comprises relatively few parts which greatly reduces the cost of manufacture and material, yet being sufficiently strong to resist the forces applied for stretching the material secured thereby. Furthermore, it will be noted that the movable clamping jaw units are easily and readily operated between the clamped or unclamped position by a simple rotary movement of the shaft.

Also, since relatively narrow jaw units are employed and are universally adjustable on the base plate, they may be positioned to assume any desired predetermined setting to conform to that contour to be formed by the forming die (not shown). Because of this important feature, the marginal edge portions of the sheet material can be reduced to a minimum and can correspond more accurately to the curvature to be formed by the die proper, thereby substantially reducing the amount of material required to be trimmed from the finished article formed thereby. Further, the need of specialized clamps for each differently shaped die is eliminated; consequently, a press having a universal type clamp as herein described can be utilized in conjunction with any of the variously shaped dies required.

Variations and modifications may be made within the scope of the claims and portions of the improvements may be used without others.

I claim:

1. A clamping jaw unit comprising a jaw member having a clamping surface; a bracket removably mounted on said jaw member; a second jaw member movably mounted on said bracket, said movable jaw member being adapted to be moved relative to said other jaw member and having a clamping surface directed toward the clamping surface of said other jaw member; spring means normally urging said second jaw member away from said first mentioned jaw member to maintain said jaw members normally spaced, and means for moving said second jaw member against the force of said spring means and toward said first mentioned jaw member, said moving means including a dowel means mounted on said bracket in engagement with the movable jaw member at the rear of the clamping surface thereof, and a shaft rotatably mounted on said bracket in fixed relation to said first jaw member and having a portion forming eccentric cam means provided with a recess for receiving said dowel means, said eccentric cam means being in camming en-

gagement with said dowel means for laterally displacing said dowel means for moving said movable jaw member relative to said other jaw member upon rotation of said shaft for clamping and unclamping an article therebetween, said recess being located to receive the dowel means in the unclamping position of the cam means and accelerating the movement of the second jaw into and out of clamping relation.

2. A clamping jaw unit comprising a jaw member; a bracket removably mounted on said jaw member; a second jaw member movably mounted on said bracket, said movable jaw member being adapted to be moved relative to said other jaw member; spring means normally urging said second jaw member away from said first-mentioned jaw member to maintain said jaw members normally spaced; means for moving said second jaw member against the force of said spring means and toward said first-mentioned jaw member, said moving means including a dowel means mounted on said bracket in engagement with the movable jaw member; and a shaft rotatably mounted on said bracket in fixed relation to said first jaw member and having a portion forming eccentric cam means provided with a recess for receiving said dowel means, said cam means adjacent the recess being in camming engagement with said dowel means for laterally displacing said dowel means for moving said movable jaw member relative to said other jaw member upon rotation of said shaft for clamping and unclamping an article therebetween, said movable jaw member being formed with an elongate dowel-receiving recess adapted to receive and engage the side of said dowel means for assuring complete engagement therebetween, said recess on the cam means being located in unclamping position to receive the dowel means under the action of the spring means to permit rapid opening of the jaws.
